CHARM

David L. Corbisier, 1092 N. Lincoln St.,
Orange, Calif. 92667

Filed Feb. 25, 1972, Ser. No. 229,626

Term of patent 3½ years

Int. Cl. D11—01

U.S. Cl. D45—17

FIG. 1 is a front face view of a charm showing my new design;

FIG. 2 is a rear face view thereof.

FIG. 3 is a top edge view thereof.

FIG. 4 is a bottom edge view thereof.

FIG. 5 is a side edge view as seen from the left of FIG. 1;

FIG. 6 is a side edge view as seen from the right of FIG. 1; and

FIG. 7 is a perspective view of the charm.

I claim:

The ornamental design for a charm, as shown.
